UNITED STATES PATENT OFFICE.

WILLIS J. PERKINS, OF GRAND RAPIDS, MICHIGAN.

SCREW-PROPELLER.

SPECIFICATION forming part of Letters Patent No. 606,297, dated June 28, 1898.

Application filed November 27, 1895. Serial No. 570,811. (No model.)

To all whom it may concern:

Be it known that I, WILLIS J. PERKINS, a citizen of the United States, residing at the city of Grand Rapids, in the county of Kent and State of Michigan, have invented certain new and useful Improvements in Propeller-Wheels, of which the following is a specification.

This invention relates to certain new and useful improvements in propeller-wheels in which the blades may be shifted at pleasure so as to propel the boat to which the same are attached either forward or backward and which are also adapted to be set in position so as to neither move the boat forward nor backward; and the objects of the invention are, first, to produce a reversible or feathering blade propeller-wheel for power-operated boats, so as to propel the boat in either direction without reversing the actuating power; second, to minimize the resistance to the rotation of the propeller-wheel in the water; third, to provide stops to regulate the pitch or lead of the blade as it is shifted upon its axis, said stops being so located as to offer no frictional resistance to any of the rotating parts of the blade or connecting mechanism; fourth, to provide a construction of such kind that one or more of the blades can be readily removed in case of mishap and others substituted; fifth, to provide a mechanism for shifting the blades of the propeller, the same being entirely inclosed, so as to leave a smooth surface on the outside, thereby preventing the same from winding up grass, weeds, or other foreign substances upon the hub; sixth, to so construct the propeller as to obtain the greatest amount of rigidity and strength with the least amount of material, the accomplishment of which objects are adapted to make this form of propeller-wheel desirable to boats operated by steam-engines, gas or gasolene engines, electricity, compressed air, or analogous means. It is evident that by shifting the blades in the reverse direction, as hereinafter described, the motion of the boat is first arrested and then reversed. Without this device or some analogous mechanism it would be necessary to stop the engine and reverse it. This operation in all ignition gasolene-engines ordinarily requires the stopping and restarting of the engine, and if engines

can be made to reverse automatically it would require much greater power than to shift the blades, as hereinafter described, and would also consume much more time. These objects I accomplish by means of the mechanism illustrated in the accompanying drawings, in which—

Figure 1 is a transverse section of my propeller-hub on line $y-y$ of Fig. 2, the blades and reversing-racks being shown in elevation. Fig. 2 is a sectional view on line $z-z$ of Fig. 1; and Fig. 3 is an elevation of my invention removed from the boat for the purpose of more fully illustrating the same, the propeller-shaft and encircling tube or sleeves being broken apart and shortened. Fig. 4 is a longitudinal section of the outside shell or case, taken approximately on line $Q'-Q'$ of Fig. 7. Fig. 5 is a longitudinal section of the collars and stuffing-box inside of the boat, being a continuation also of the shaft Q and tube M . Fig. 6 is an end view of the collar L , showing an end of the racks J and K and a sectional view of shaft Q . Fig. 7 is an end view of Fig. 4 with the cap removed with the blade A partly sectioned, showing the journals of the blades, their connection, and their relative position with reference to the racks. 80

In the several figures above named A and B represent the propeller-blades. These blades have their inner ends formed into the journals C and D integral with the blades and adapted to turn in suitable journal-boxes E and F . The extreme inner end 1 of the blade B is supported in the journal-box G , while the inner end 2 of the blade A —that is, the inner ends or journals 2 and 1 of the two blades—are formed male and female, respectively. By this construction the two blades not only turn upon the same center, but their journals are united together, said journals fitting into each other, thereby giving a great amount of strength and stability to the attachment of the blades to the hub and at the same time employing but a small quantity of metal, whereby I obtain a high degree of strength and rigidity with only a minimum weight. 100

The journal-box G is circular in form. It is adapted to fit into a recess in the two-part hub, the two-part hub being shown by E and F and the same being so constructed that by

drawing the two parts together this circular journal-box G will be compressed and held from rotating. This may be done by screws or bolts in the ordinary manner. Each blade-journal is provided with a gear, said gears being shown by H and I, the gears being made either integral with or rigidly secured to the blades, respectively. Engaging with the teeth on the gear are two racks K and J, they being placed on opposite sides of their axis. The racks J and K are fastened into a collar L, which collar L has a longitudinal movement upon the propeller-shaft Q. A sleeve or tube M is attached to or may be made integral with the collar L, said sleeve being preferably long enough to project into the boat to a suitable point. The collar N has a peripheral groove W in its circumference and is rigidly secured to the sleeve M or made integral therewith, and suitable shifting mechanism of any well-known form or design is suitably located to engage with said peripheral groove, so as to give longitudinal movement to the tube or sleeve M and thereby to the shifting mechanism.

O and O' represent two separate stuffing-boxes, the box O being outside the boat and the box O' inside. The stuffing-box O is formed by a cavity in the end of the sleeve S, which is entered by the threaded hub of the stern-post box R.

The stuffing-box O' is formed by the collar N and a sleeve O², which is screwed into the collar N, the latter forming the other part of said stuffing-box. This box is arranged inside the boat.

P is an adjustable collar located upon the shaft Q. This collar forms a stop which limits the movement of the pinions in one direction, and by means of its adjustment the revolving motion of the propeller-blades may be regulated. The movement of the pinions in the opposite direction is limited by the collar L abutting against the sleeve S, as already described.

R is the stern-post box, its upper end in the illustration being formed into one-half of the stuffing-box S' and provided with a screw-thread upon it, which screw-thread engages with the screw-thread in the collar S, which collar or sleeve S forms the balance of the stuffing-box, suitable packing material being used between the two parts, as shown by S' in Fig. 2. The collar or sleeve S is preferably extended over the hub F, so as to completely envelop and protect the shaft and the racks J and K from any drift or debris that might be in the water and also preventing unnecessary churning of the water.

60 By making the hub in two parts, as E and F, it divides the journal-box, which forms the support for the journals C and D, into two portions. By this construction the removal of suitable holding-bolts, which attach the parts of the hub E and F together, the part E may be removed entirely from the part F of the hub, leaving perfect freedom for the re-

moval or insertion of the propeller-blades A and B, the bolt-holes T T, &c., being screw-threaded, so that the bolts passing through the hub E may engage therewith. By this construction any one or more of the blades or paddles may be readily removed in case of injury and new ones substituted.

It will be noticed that the racks J and K are placed on opposite sides of the axis of the blades A and B. This is desirable, as the required alteration in the angle of the blade must be in opposite directions.

The operation of my invention is as follows: The handle for shifting or reversing the blades is carried to any portion of the boat where the same would be most convenient for the pilot or person in charge. By shifting the operating-handle so provided the sleeve M is moved longitudinally on the shaft Q. The racks K and J engaging with the pinions H and I upon the propeller-blades A and B turn said blades in opposite directions, thereby reversing the pitch or lead of the blade and reversing the movement of the boat. The collar L, which is arranged in the sleeve S, abuts against and is arrested by the hub F, thereby gaging the angle to which the blades may be shifted in one direction. On the reverse shift the sleeve M is limited in its movements by the collar N on the stuffing-box O', which strikes against the adjustable collar P on the propeller-shaft Q, thereby arresting the longitudinal movement in that direction. As the hub F and collar L turn together, there is no resistance caused by this adjustment to the rotation of the propeller-shaft Q, and as the collars N and P also turn with the shaft there can therefore be no frictional resistance offered by them. It will be noted that the axis of the propeller-blades A and B are on a direct straight line. The blades are made as much one side of the center line as the other, and therefore are "balanced," so to speak, upon their journals. Consequently the shifting is made without any material effort or exercise of power and the strain on the reversing-gears is proportionately decreased.

In the drawings I have shown but two blades, that being the number ordinarily used in small boats; but more blades may be similarly mounted and connected, if desired.

While I have described my preferred form, I do not wish to limit myself to the exact form shown in the drawings and described in the specification, but wish to reserve all rights pertaining to the invention I have made.

Having thus described my invention, what I claim to have invented, and desire to secure by Letters Patent, is—

1. The combination with a propeller-shaft stopping short of the journal-bearings for the blades and provided at its ends with a rigidly attached journal-box, or hub, of opposite propeller-blades having male and female pivotal bearings upon their journal ends, and gearing thereon, racks having longitudinal movement and engaging said gearing, a non-

- rotating sleeve capable of longitudinal movement on and partially covering said hub, substantially as described.
2. The combination with a propeller-shaft and hub thereon forming pivotal supports for propeller-blades, of a sleeve encircling said shaft and partially revolving said blades through suitable mechanism, and an adjustable collar or stop on said shaft to determine amount of said blades' rotation.
3. The combination with a propeller-shaft and a hub rigid thereon, of two propeller-blades journaled in said hub near its periphery on opposite sides of a central and third journal-bearing positively connecting said propeller-blades, means for turning the blades in either direction, and an adjustable collar on said shaft to limit their turning movement, substantially as described.
4. The combination with a propeller-shaft, and a plurality of shifting propeller-blades suitably journaled, of a hub rigid on said propeller-shaft, and a removable non-rotating section or collar at the center of the propeller-blade journal-box, said collar partly inclosing and capable of longitudinal movement on said hub, substantially as described.
5. The combination with a propeller-shaft, of two propeller-blades, each provided with a journal-bearing, two pinions placed within the journal-boxes within a hub on said shaft, two racks adapted to engage with the respective pinions on opposite sides of the axis of the hub, an inward extension of one of the journals of one of the propeller-blades having a socket or opening and an inward extension of the journal on the other of said propeller-blades adapted to engage with said socket or opening, thereby forming auxiliary journals of the propeller-blades within the hub, substantially as described.
6. The combination with the blades of a propeller-wheel, of a hub composed of two parts E and F separably secured together, journals on said propeller-blades rigidly attached thereto, adapted to turn said blades, racks adapted to engage with the pinions on the journals of said propeller-blades, a movable sleeve or collar to which the said racks are secured, a sleeve partly inclosing and capable of longitudinal movement upon the journal-box, or hub, and also inclosing the said racks and a portion of the propeller-shaft, suitable stuffing-boxes preventing the water from passing through into the boat, a sleeve connected with the said collar and extending into the boat, and suitable means for giving the longitudinal movement to the said sleeve and thereby to the racks for the purpose of setting the propeller-blades in any required position, substantially as described.

In witness whereof I have hereunto set my hand and seal in the presence of two witnesses.
